United States Patent Office.

REUBEN S. WHITTIER, OF DORCHESTER, MASSACHUSETTS.

Letters Patent No. 82,053, dated September 8, 1868.

IMPROVED WINDOW-SCREEN.

The Schedule referred to in these Letters Patent and making part of the same.

TO ALL WHOM IT MAY CONCERN:

Be it known that I, REUBEN S. WHITTIER, of Dorchester, in the county of Norfolk, and State of Massachusetts, have invented certain new and useful Improvements in Window-Screens, of which the following is a full, clear, and exact description, reference being had to the accompanying drawings, making part of this specification, in which—

Figure 1 represents the outside of a portion of an ordinary window having my improvements applied thereto.

Figure 2, an inside view of the same, the screen having been detached from the sill and carried up by the roll.

Figure 3, a horizontal plane section.

Figure 4, a vertical transverse section, on the line A' B' of figs. 1 or 3.

Figure 5 is a central longitudinal section of the screen-roll, the spring-shaft, and bushings, and of the end plates, which form supports for the roll.

Figure 6 is a back side view of the case containing the roll, but detached from the window, the roll being shown as supported by the plates at the ends of the former; showing, also, the slotted spring-plates which connect the case and the roll with the lower rail of the sash.

Figure 7 is a bottom side view of what is shown in fig. 6.

Figure 8 is an end elevation of fig. 6, and

Figure 9 the opposite end.

This invention relates to that class of window-screens, the special object of which is to exclude mosquitoes and other insects from enclosures, while admitting as much as possible the circulation of air through the screen, which covers an open space.

The objects of this invention are—

First, simplicity and economy in the construction of the self-winding roll, and in the application of the shaft and the spring to the end of the roll.

Second, protection of the screen and the roll in stormy or rainy weather.

Third, more perfectly covering the aperture or opening below the raised window-sash.

Fourth, greater convenience in attaching the case and the roll to the sash, and the lower end of the screen to the window-sill, and of detaching the same at pleasure.

Fifth, to provide a rolling window-screen, which, when the sash is raised, may be easily drawn down and attached to the window-sill, and detached from the sill or its lower connection by simply lowering or closing the sash.

This invention consists—

First, in the construction and combination of the parts which form the self-winding roll, A, the same being composed of the shaft, B, bushings, C and D, spiral spring, E, the disk, F, and the body, A, of the roll.

Second, in the case or cover, G, when applied to the sash so as to protect the screen and the roll, and, in combination with the case or cover, of a slotted plate, a, and a concave plate, b, as supports for the roll, and for other objects hereinafter described.

Third, my invention consists in the peculiar arrangement and combination of the roll, screen, and case with the sash and the window-frame, whereby the screen is made to more perfectly cover the open space after the sash is raised, and that the lower end of the screen may be disconnected from the sill by simply lowering or closing the sash.

Fourth, my invention consists in the slotted curved spring-plates d applied to the case G, and arranged to connect with screws e, or holding-devices, projecting from the sash.

Fifth, my invention consists of the slotted plates f, applied to the bar H, in combination with the connecting and holding-devices, e, when arranged relatively to the bevelled side, g, of the case, so as to detach the latter bar from the holding-devices, and allow the screen to rise by simply closing or lowering the sash.

In constructing and applying my improved window-screen, I first take an ordinary roll, squared at both ends, and of a suitable length, and in one end a hole is bored about six inches deep.

At the inner end of this hole, and against the solid substance of the wood, I place a metal disk, F, and against this disk a bushing, C, which serves as a bearing for the shaft B, the inner end of which bears against the disk.

The roll may turn on the bushing, or the bushing may turn on the shaft.

A spiral spring, E, winds around the shaft B, to furnish the power for turning the roll to wind up the screen.

One end of the spring is attached to the inner end of the shaft B, and the opposite end, 2, is bent back, and secured in a groove made in the outside of a bushing, D, which forms a bearing for the outer end of the shaft. This latter bushing is fastened to the roll proper, and the shaft fits loosely within it.

The extreme end of the shaft is square, and fits in a square bearing in the end-plate a, (see figs. 5 and 9,) so that the roll may turn in either direction, to wind up the screen or allow it to unroll without turning the shaft; for, as it will be seen, confining one end of the shaft is necessary, in order to bring the power of the spring into action to turn the roll, and wind up the screen when detached from the sill, M, or the holding-devices, e.

The plate a, at or about its centre, and around the square shaft-bearing, is concave on the outside and convex on the inside. This allows of greater length of the square shaft-bearing and of bearing-surface, to accommodate any endwise motion of the shaft or the roll, without having the outer end of the shaft come in contact with the pulley-stile, L, when the sash, K, and the case and roll are raised or lowered, which is of some importance.

The opposite end of the roll A is supported by a plate, b, both of the plates a and b being fastened to and flush with the ends of the sloping top, g, of the case G.

The plate b is slotted from its lower end upward to near the central bearing-screw l. This admits of the screen being removed from the roll, or replaced therein, without detaching the plate or disconnecting the roll from the case, the roll being grooved longitudinally, to receive the top end of the screen, in the usual way.

The lower end of the screen may be attached to the bottom bar, H, in the same, or in any convenient manner.

The bearing-screw l is intended to regulate the action of the roll, operated by or against the action of the spring, by tightening or loosening said screw, and thereby increasing or diminishing the friction between the end of the roll and the inner surface of the plate b.

To the inner edge, 3, of the top portion, J, of the case which covers the roll, slotted curved spring-plates d are secured, and screws e, or other connecting and holding-devices project from the outside of the sash. The case is connected with the inner sash by sliding it downward in the space occupied by the outer sash, the curved spring-forks n of the plates d passing each side of the screws e, and under or back of the screw-heads, thus connecting the case with the sash, the spring-forks drawing and holding the parts closely together.

The case and the roll may be detached from the sash by sliding them upward, as the yielding action of the spring-forks allows of their being easily removed or replaced.

After the case and the roll have been connected with or attached to the sash, as described, the screen is drawn downward by the hand laying hold of the bar H, the lower side of said bar is brought down on to the top of the sill M, and then slid outward over the screws e, which rise from the sill. The shouldered sides m of the slotted plates f passing beneath the heads of the screws connects this bar and the lower end of the screen with the sill.

This improved screen may be disconnected from the sill by sliding the bar H back a little, and allowing the screen to wind upon the roll without moving the sash. Or if, by reason of a change in the weather, or for any other reason, it should be desired to close the window, simply sliding the sash down to the sill brings the inner level of the lower edge of the portion g of the case into contact with the outer edge of the bar H, and slides said bar inward, releasing the shoulders m of the plates f from the heads of the screws e, and detaching the bar H and lower end of the screen from the sill.

This mode of detaching the screen I consider very important, for it leaves the window available for observation at either side as well as directly forward, or as a passage for articles in the day-time, or when the screen need not be drawn over the open space. And it is my intention to detach the lower end of the screen and allow it to roll up whenever the window is closed, or whenever desired, without lowering the sash, thus making the rolling window-screen attachable to and detachable from the sill or the holding-devices, at the pleasure of the user, and detachable by closing or lowering the sash, as described.

It will be observed that when the sash is raised, and the screen S is unrolled and drawn downward, the extreme sides of such screen lie fair against the inner sides or surfaces of the outside casings N, and thereby cover more perfectly the open space, and more effectually exclude mosquitos and other insects.

The bar H has transverse grooves, O, seen in figs. 1 and 4, which allow said bar to slide forward over the heads e of the screws rising from the sill, and the plates f to slide under them, or in the opposite direction, to detach the bar and the screen from the sill.

When the case, roll, and screen are applied as shown and described, and the sash is closed, the roll and screen are well protected by the case, which fits the outside of the sash, and closes tight down on the top of the sill, keeping the screen and the roll dry.

I am aware that rolling window-screens have been used, the roll operated by a coil or a spiral spring, and that such screens have been rendered attachable and detachable, by bolts at the ends of the lower bar, and by a hook or several rings, to connect the top of the screen to the sash.

I am also aware that a rolling screen has been made to cover the opening produced by raising the sash.

I disclaim having invented either of the above devices or improvements; but
What I do claim, and desire to secure by Letters Patent, is—

1. The combination and arrangement of the shaft B, bushings C and D, disk F, and spring E, with the body A of the roll, in the manner and for the purpose specified.
2. The plate *a*, provided with a concave bearing, in combination with the square-ended shaft B and its connections, and with the case G, for the purpose and substantially as described.
3. The plate *b*, provided with a slot, *p*, when used in combination with the roll A, and with the case G and the screen S, for the purpose and substantially as described.
4. The curved spring-plates *d*, slotted as shown and described, in combination with the case G and the screws *c* or holding-devices, which connect the case and the roll with the sash, as described.
5. The slotted plates *f*, constructed as described, in combination with the bar H and the screws *e*, for the purpose and substantially as described.
6. The combination, with the sash K, of a case, G, constructed as described, the case serving as a cover and protection to the roll and the screen, and also as a device for detaching the bar H and the screen from the sill, for the purpose and substantially as described.
7. The arrangement and combination of the roll, screen, and case, and the supporting-plates, with the sash, and the bar H with the sill M, so that the screen shall more perfectly cover the open space produced by raising the sash, as and for the purpose set forth.
8. The combination of all the operative parts specified, arranged to operate substantially as and for the purpose set forth.

REUBEN S. WHITTIER.
